UNITED STATES PATENT OFFICE

2,266,703

REFRIGERATOR CABINET

La Mar S. Cooper, Erie, Pa., assignor to General
Electric Company, a corporation of New York

Application September 6, 1940, Serial No. 355,559

9. Claims. (Cl. 62—89)

My invention relates to refrigerator cabinets and more particularly to devices for preventing condensation of moisture on the outside of such cabinets.

This application is a continuation-in-part of my copending application Serial No. 332,778, filed May 1, 1940, and assigned to the same assignee as my present invention.

Refrigerator cabinets, particularly those provided with a plurality of doors, frequently have portions of their outside surfaces which may be cooled to temperatures below the dewpoint of the surrounding air, resulting in the condensation of moisture on these surfaces. For example, the mullion provided between the doors of a two-door cabinet has an outside surface which is insulated from the remainder of the outside surfaces of the cabinet by the door gaskets. Furthermore, since the door does not normally contact the jamb but rests on the door gasket, there is a space between the door and the surrounding gasket through which cold air may circulate from the cabinet interior thereby increasing the cooling effect along the mullion. While the cold air also cools the door surface there is sufficient surface exposed to the surrounding air for the absorption of heat, thereby preventing excessive cooling, but the other surface of the mullion is separated along both sides by the gaskets and little heat can flow thereto over the cabinet and door surfaces. Therefore, the outside surface of the mullion will be cooled to a greater degree than the outside surface of the remainder of the refrigerator cabinet and in many cases this cooling effect will be sufficient to lower the temperature of the outside surface of the mullion below the dewpoint of the surrounding air and thereby to cause condensation of moisture. Moisture formed on the mullion surface is obviously undesirable and may in some cases prove injurious to the cabinet and its fittings. Should the formation of moisture be excessive, it may also run down and collect on the floor.

Accordingly, it is an object of my invention to provide a new and improved arrangement for preventing condensation of moisture on the outer surfaces of refrigerator cabinets.

Further objects and advantages of my invention will become apparent as the following description proceeds and the features of novelty which characterize my invention will be pointed out with particularity in the claims annexed to and forming a part of this specification.

For a better understanding of my invention reference may be had to the drawing in which

Fig. 1 is a front elevational view of a two-door refrigerator cabinet embodying the principles of my invention; Fig. 2 is an enlarged sectional view of the center mullion illustrated in Fig. 1 and an adjacent door; and Fig. 3 is an enlarged sectional view illustrating a different embodiment of my invention.

In accordance with my invention and in order to provide an outer surface over the relatively narrow center mullion 10 of the refrigerator cabinet 11 at a temperature normally above the dewpoint of the air surrounding the cabinet, I have provided the outer surface of the mullion with a shield or covering 12 formed from material having relatively poor heat conducting characteristics or relatively good heat insulating qualities such as rubber, for example. In the form of my invention illustrated in Figs. 1 and 2 of the drawing the aforementioned covering comprises a pair of gaskets 13 and 14, each of which extends around a door opening of the cabinet 11. The gaskets 13 and 14 are constructed to lie in closely abutting relationship along the outer surface of the mullion and thereby substantially cover the outer surface of the mullion. In Fig. 3 there is illustrated a single shield or covering member 31 covering the outer surface of the mullion.

Describing my invention in greater detail I have provided a refrigerator of the domestic type comprising heat-insulated walls and a plurality of door openings closed by thermally insulated doors 15 and 16, the doors being suitably hinged to the cabinet. In order to provide adequate cooling for the food storage compartments 17 and 18, I have provided cooling elements or evaporators 19 and 20 in the compartments 17 and 18, respectively. Inasmuch as the details of the refrigerating system form no part of my present invention only the cooling elements or evaporators are illustrated in the drawing. Any suitable form of apparatus may be employed.

The cabinet door walls comprise an outer casing or wall 21 and an inner liner or wall 22 having suitable heat insulation 23 disposed therebetween. The walls 21 and 22 are maintained in spaced-apart relationship by a breaker strip 24 of non-metallic, non-hygroscopic material, such as a resinous product known under the names "Bakelite," "Textolite," etc., in order to reduce the conduction of heat into the cabinet. The outer casing 21 of the door is provided with a flanged portion 21a extending substantially half way across the outer surface of the mullion 10 so that the adjacent edges of the

doors are spaced apart but a small distance, i. e., are closely adjacent, and the doors substantially cover and conceal the mullion in the closed positions of the doors and arranged to engage the gasket associated therewith for deforming the striking bead and sealing the space around the door opening. With this construction, heat is conducted to the covering by the outer casing 21 of the door.

The mullion 10 is provided between the openings into the refrigerated compartments 17 and 18 and comprises an outer metallic wall 25 and an inner metallic wall 26 having suitable heat insulating material 27 therebetween. The inner and outer walls of the mullion are separated by breaker strips 28 of the same material as that used for the breaker strips 24. The breaker strips 24 and 28 may be secured to the walls of the doors and mullion respectively in any suitable manner as by means of threaded fastening members, for example.

In order to seal the space between the doors and the cabinet walls and also between the doors and the mullion 10, referring to Figs. 1 and 2, I have provided a pair of gaskets 13 and 14 extending entirely around the door openings. The gaskets may be of any suitable material having relatively poor heat conductive characteristics and formed in any desired fashion. However, in accordance with my invention, the gaskets are so arranged as to cover substantially the entire outer surface of the wall 25. The gaskets shown in Figs. 1 and 2 comprise an anchoring portion 29 and a striking bead 30. The anchoring portion is arranged to be clamped between the breaker strip 28 and the outer wall 25. The striking bead 30 is preferably hollow, thereby increasing the resiliency of the gasket material and also providing a layer of dead air which is of assistance in minimizing the transfer of heat between the interior and the exterior of the refrigerator cabinet.

Tests made on a refrigerator similar to that shown and provided with a gasket and covering or shield 12 similar to that illustrated in Figs. 1 and 2 of the drawing disclosed sweating on the exposed surface of the gaskets between the two doors at approximately 70 per cent relative humidity in an ambient temperature of 100° F. whereas sweating occurred at approximately 55 per cent relative humidity in the same ambient temperature with the metallic outer surface 25 of the mullion 10 exposed to the surrounding air, the box air temperature being about 45° F. in each case.

In Fig. 3, there is shown an arrangement in which the outer surface or web of the mullion 10 is covered by a single shield or covering 31 having anchoring portions 32 clamped between the breaker strips 28 and the outer surface of the wall 25. The single covering member or striking portion 31 is hollow in shape and provided with internally disposed reinforcing means such as a pair of angularly disposed members or arms 33 extending between the portion or web adjacent the mullion and the outer portion or web of the covering for supporting the latter. In the illustrated arrangement, the arms are disposed for establishing a heat flow path between the aforementioned portions which is relatively 70 long, that is, long as compared with the path or bridge existing in the arrangement shown in Figs. 1 and 2 and in such a way that there is normally no direct heat conductive path between the exposed surface of the covering member and the 75

metal surface 25 of the mullion, that is, when the doors are closed. The arms 33 are formed of material having relatively poor heat conductivity characteristics and may be formed integrally with the covering member 31, the region of engagement between the arms and the outer covering or portion being covered by the doors or closure means whereby heat must travel along a portion of the outer covering in order to reach the arms 33. When this last described arrangement was tested, sweating did not occur until a relative humidity of 75 per cent in an ambient temperature of 100° F. was reached, the box air temperature being approximately 45° F.

While I have illustrated the combined gaskets and shields as being supported on the refrigerator cabinet, the arrangement of Figs. 1 and 2 may be secured in the more conventional fashion to the doors. However, the arrangement illustrated is preferred because it is difficult to obtain a close enough disposition of the gaskets along the adjacent edges of the doors in the closed positions thereof. A further advantage of having the gaskets on the mullion is that a warmer surface is exposed to the atmosphere when the door or doors are opened than will be the case if the gaskets are on the doors so that a higher relative humidity is required to produce sweating than would be the case if the face 25 of the mullion, which is at a lower temperature, were exposed.

While I have shown a particular embodiment of my invention I do not desire my invention to be limited to the particular construction shown and described and I intend in the appended claims to cover all modifications within the spirit and scope of my invention.

What I claim as new and desire to secure by Letters Patent of the United States, is:

1. In combination with a refrigerator cabinet of the type having a plurality of door openings, closure means for closing said openings, a mullion between the door openings, and a cooling element for cooling the interior of the cabinet, a portion of the outer surface of the mullion so disposed that it may be cooled below the dew-point of the surrounding air by the operation of the cooling element, means for preventing the condensation of moisture on said mullion, said means comprising a shield of relatively poor heat conducting characteristics provided exteriorly of said mullion whereby the surface of the shield exposed to the surrounding air at said mullion is maintained at a temperature normally above the dewpoint of the surrounding air, said shield also serving as a seal to prevent the surrounding air from entering the interior of the refrigerator cabinet.

2. In combination with a refrigerator cabinet of the type having a plurality of door openings, a mullion between the door openings, and a cooling element for cooling the interior of the cabinet, a portion of the outer surface of the mullion so disposed that it may be cooled below the dew-point of the surrounding air by the operation of the cooling element, means for preventing the condensation of moisture on said mullion, said means comprising a covering exteriorly of said mullion, said covering comprising a material having relatively poor heat conducting characteristics, whereby said covering is maintained at a temperature normally above the dewpoint of the surrounding air, said covering also acting as a seal to prevent the surrounding air from

entering the interior of the refrigerator cabinet.

3. A thermally insulated cabinet having a pair of door openings, door means adapted to close said openings, a mullion provided between the door openings, a cooling element in said cabinet, the outer surface of said mullion being so disposed that it may be cooled below the dewpoint of the surrounding air by operation of the cooling element, a gasket extending around each of the door openings, the portions of said gaskets adjacent the outer surface of said mullion being formed from material having relatively poor heat conducting characteristics and being so constructed and arranged as to cover substantially the entire of said outer surface whereby the exposed surface of said gasket is maintained at a temperature normally above the dewpoint of the surrounding air.

4. A thermally insulated cabinet having a pair of door openings, door means adapted to close said openings, a mullion provided between the door openings, a cooling element in said cabinet, the outer surface of said mullion being so disposed that it may be cooled below the dewpoint of the surrounding air by operation of the cooling element, a gasket extending around each of the door openings, the portions of said gaskets adjacent the outer surface of said mullion being formed from material having relatively poor heat conducting characteristics and being so constructed and arranged in closely abutting relationship along said outer surface to cover substantially all of said outer surface whereby the exposed surface of said gasket is maintained at a temperature normally above the dewpoint of the surrounding air.

5. A thermally insulated cabinet having a pair of door openings, door means adapted to close said openings, a mullion provided between the door openings, a cooling element in said cabinet, the outer surface of said mullion being so disposed that it may be cooled below the dewpoint of the surrounding air by operation of the cooling element, a gasket comprising a hollow striking bead extending around each opening, the portions of said gaskets adjacent the mullion being so constructed and arranged as to cover substantially all of said outer surface, and formed of material having relatively good heat insulating characteristics for restricting transfer of heat between the exterior and interior of said cabinet through said mullion, said hollow bead providing a dead air space for further restricting the aforementioned transfer of heat, said gasket thereby serving to maintain on the outer surface of said mullion a covering at a temperature normally above the dewpoint of the surrounding air.

6. In combination with a refrigerator cabinet of the type having a cooling element for cooling the interior of the cabinet and a portion of the outer surface of the cabinet so disposed that it may be cooled below the dewpoint of the surrounding air by the operation of the cooling

element, means for preventing the condensation of moisture on said portion, said means comprising a covering exteriorly of said portion, said covering comprising a material having relatively poor heat conducting characteristics and having a hollow striking portion, said striking portion being provided with angularly disposed means of relatively poor heat conductivity extending between the outer web of said striking portion and the inner web of said striking portion adjacent the mullion, whereby said covering is maintained at a temperature normally above the dewpoint of the surrounding air.

7. In combination with a refrigerator cabinet of the type having a plurality of door openings, closure means for closing said openings, a mullion between the door openings, and a cooling element for cooling the interior of the cabinet, a portion of the outer surface of the mullion so disposed that it may be cooled below the dewpoint of the surrounding air by the operation of the cooling element, means for preventing the condensation of moisture on said mullion, said means comprising a hollow covering on said mullion, said covering comprising a material having relatively poor heat conducting characteristics and also being provided with internally disposed reinforcing means extending between the inner and outer surfaces of the covering, the region of engagement between the reinforcing means and the outer covering being covered by said closure means.

8. A thermally insulated cabinet having a plurality of door openings, door means arranged for closing said openings, a mullion provided between the door openings, a cooling element in said cabinet, and means for maintaining the outer surface of said mullion at a temperature normally above the dewpoint of the surrounding air, said means comprising a covering of relatively poor heat conducting material on the outer surface of said mullion, said doors and said mullion being so dimensioned with respect to each other that said covering is substantially covered and concealed in the closed positions of the doors, said means also serving as a seal to exclude the surrounding atmosphere from the interior of the cabinet.

9. A thermally insulated cabinet having a plurality of door openings, door means arranged for closing said openings, a mullion provided between the door openings, a cooling element in said cabinet, and means for maintaining the outer surface of said mullion at a temperature normally above the dewpoint of the surrounding air, said means comprising a covering of relatively poor heat conducting material on the outer surface of said mullion, said doors and said mullion being so dimensioned with respect to each other that the adjacent edges of the doors are closely adjacent when the doors are closed, said means also serving as a seal to exclude the surrounding air from the interior of the cabinet.

LA MAR S. COOPER.
